UNITED STATES PATENT OFFICE.

JOHN BURKITT WEBB, OF MILLBURN, NEW JERSEY.

DYNAMOMETER.

SPECIFICATION forming part of Letters Patent No. 669,568, dated March 12, 1901.

Application filed December 29, 1897. Serial No. 664,866. (No model.)

To all whom it may concern:

Be it known that I, JOHN BURKITT WEBB, a citizen of the United States, residing at Millburn, in the county of Essex and State of New Jersey, have invented a new and useful Dynamometer, of which the following is a specification.

My invention relates to improvements in dynamometers in which the power developed by a motor is absorbed and measured; and it consists of certain novel parts and combinations of parts particularly pointed out in the claims.

In the drawings accompanying this specification, Figure 1 is a vertical side view, mostly in section, of the dynamometer coupled to a gas-motor, shown at the right in outline, for the purpose of measuring the power of the latter; Fig. 2, an end view of the dynamometer alone; Fig. 3, an enlarged vertical section of the "restricted level" shown at L in Figs. 1 and 2. Figs. 4 and 5 are sections of the level-tube in Fig. 3.

Dotted and broken lines are used to indicate the lines on which the sections are made, and similar letters refer to similar parts throughout the several views.

The dynamometer herewith illustrated consists of a shaft S, which may be connected by a coupling C or otherwise to the driving-shaft of any prime or other motor whose power is to be measured. This shaft runs freely in suitable bearings (plain holes are shown with no collars) at B and B in the water-tight case B E B E and has mounted upon it and revolving with it a gang A of good-sized circular saw-blades or other equivalent disks. Four disks are shown in this gang. For quick speeds a single disk may suffice, in which case the unnecessary disks can be dispensed with, and for slow speeds four may be insufficient, in which case the water-tight case must be made long enough to accommodate a large number of disks, (perhaps fifty to one hundred,) which may also be set closer together to increase the resistance. These disks are mounted upon a hub, into which the shaft is firmly fastened, and are kept at the proper distance apart by washers, the disks and washers being tightly bolted to the hub. This arrangement is shown in section in Fig. 1, with the heads of two bolts show-

ing at the left end of the hub D. The disks are shown pierced with a few equalizing-holes to allow a freer distribution of the water in the case. The disks can be run without holes if collars or other means of preventing end-play of the shaft be provided. Otherwise slight irregularities in the distribution of the liquid may throw the revolving plates out of position and even bring them into contact with the stationary ones. Fig. 2 shows holes in the outer plate or disk A. The case B E B E is also fitted with a gang of annular disks (three in this case) intermediate between the revolving disks and perforated in the same manner. They are kept at the right distance apart by rings, (seen at E E, Fig. 1,) which fit snugly the inner cylindrical wall of the case and are clamped sufficiently tight by the cover 70 of the case when bolted on, as shown. The hole in these stationary disks is sufficiently large to fully clear the hub, and the inside diameter of the separating-rings is larger than the outside of the revolving disks, so as to have 75 no chance of any contact between the revolving and stationary parts. The exteriors of the bearings B B in the case are turned to fit the hangers F F, which stand upon the base G, and thus support the case. Balls are 80 introduced to relieve the friction and allow the case to swing freely between the two stops shown on the base at G. When only one revolving disk is used, the case itself furnishes the stationary surfaces and no inserted disks 85 are needed. Instead of the disks any surfaces of revolution may be used, but disks are the simplest.

The cock H furnishes water into a funnel, from which it flows into the case and is distributed equally around the interior thereof by centrifugal action. When much power is absorbed, as it will be at high speeds, the cock H is set to furnish enough water per minute to absorb the power without becoming unduly heated, and its escape is regulated by the cock J so as to keep the proper depth of water in the case to give the resistance required. To further facilitate this regulation, a number of holes (three are shown) are provided, in any one of which the escape-pipe can be screwed. Hose connections may also be used; but any disturbing action on the case by the water-jets or hose should be avoided.

To measure the moment with which the stationary disks or surfaces are sucked or dragged around after the revolving ones, a spring-balance may be used, or a scale-beam 5 K, with suitable weights, may be attached to the case, as seen in Fig. 2, the weight M being used to balance the case to its zero position when the shaft is not running and the scale-weights are set to zero. The horse-power supplied to the shaft is obtained by multiplying the number of revolutions by 2π and by the moment measured on the scale-beam, as customary in all such dynamometers.

15 To accurately indicate the central or zero position of the scale-beam, an accurate level is needed. (Shown at L in all the figures and in detail in Figs. 3 and 4.) This level is of a special and improved construction, which I 20 designate as a "restricted level." The extreme sensitiveness of a dynamometer, in which there is virtually no static friction, makes it liable to various oscillations difficult to avoid, even when the power supplied is 25 quite regular; but in many cases there is also an unavoidable slight irregularity in the power supplied, which necessarily causes oscillations, so that an ordinary level sufficiently sensitive is kept in such constant motion that it cannot be read accurately. To 30 overcome this defect of an ordinary level, the restricted level used is constructed as shown in Figs. 3, 4, and 5, where the level is shown in section, longitudinal through its center in 35 Figs. 3 and 5 and crosswise through its center in Fig. 4. Instead of hermetically sealing the ends of the glass tube n the brass end pieces o and p are cemented to it. One of these, p, is made to unscrew, and thus allow 40 access to the interior of the tube. The end pieces have the usual adjusting-screws for setting the level properly in position on the scale-beam K. Inside the level-tube a channel r r is formed to confine somewhat the 45 bubble. This is shown in cross-section in Fig. 4 and may consist (regarding these views as full-sized) of a central strip of brass the full length of the level-tube and about a quarter of an inch wide by an eighth of an inch thick. 50 This strip fits a notch in o to keep it horizontal and is held fast by the screw t. At each end of the strip a hole is bored through it for the slow passage of the oil or other liquid contained in the tube, and at one end this is 55 slotted out to allow the flattened end of the conical plug q to enter and act somewhat as a cock, so that the area of the passage at that end can be controlled somewhat by revolving the plug q from the outside by means of its 60 slotted head. The strip is also filed somewhat narrower at the ends (see Fig. 5) than it is in the center, and to complete the channel a vertical strip of brass is screwed to each edge of it, as indicated by the heavy vertical 65 lines in Figs. 4 and 5, with the screw-heads showing. Four screws in all are sufficient,

placed at the ends, as indicated by the two black dots in Fig. 3. The side pieces being sprung and the strip narrower at the ends, the channel can be closed slightly at the ends 70 by means of these screws. This furnishes a means of varying the sensitiveness of the level without depending on the exact curvature of the glass tube. In fact, the tube may be of any slight curvature or even straight, 75 and the proper sensitiveness can be obtained by adjusting these side or cheek pieces to narrow the channel toward the ends by the proper amount. Of course a single piece can be used with the suitable channel in it; but 80 it is better made in three pieces, as shown, and they do not need to fit the glass tube tightly to sufficiently confine the bubble. Some liquid may get past the bubble underneath it, as the bubble need not fit against the 85 strip as closely as shown in Fig. 4; but the main part has to flow down through the hole at one end and up through the hole at the other when the bubble moves, so that it cannot violently oscillate and will yet creep to 90 the correct position in a fraction of a minute. It can evidently be arranged to control the curvature of this channel from the outside, so as to make the sensitiveness adjustable at will without opening the level-tube. Of 95 course a curvature could be given to the upper face of the brass strip, and this face is also a suitable place for the graduations showing the exact position of the bubble. Of course I do not hold to the particular materials and construction described, so long as the essential features are secured, and the level-vial may easily be made entirely of glass and hermetically sealed, with the return-passage arranged inside of it or through a separate tube or passage outside of it. 105

This dynamometer is self-starting, inasmuch as the liquid offers no resistance when at rest in contradistinction to solid friction-dynamometers in which the friction must be relieved at starting.

The particular construction described can be varied in many ways, some of which are: The case may be supported on rollers, knife-edges, or springs or by floating or other frictionless way. The bearings B B may be omitted and the shaft arranged to run without touching the case, water not being liable to escape around the shaft at B. The shaft need not be horizontal. The case may be supported principally from one side. It may be hung on the shaft by the bearings B B, their friction counting in with that of the water. To put any of the disks out of action, some of the annular plates can be without holes and the water supplied only to those revolving plates which are to act, which is equivalent to making the dynamometer "compound," with separate compartments and a water supply and escape for each. End pressure on 130 the shaft is prevented by holes in the revolving plates, and the stationary ones do not

need holes if the water be furnished to different parts of the case otherwise. To regulate the power absorbed, the compartments may be filled with water one after the other.

5 Instead of the restricted level a mirror reflecting a beam of light upon a fixed or fed sensitive plate may be used to record the average position of the case or a mechanical trace made on smoked glass. Any holes, 10 roughening, or other cutting of the plates, such as saw-teeth on the outside, makes no essential change in their nature. While there must be chance for the water to properly distribute and while the plates are not run 15 excessively close to avoid danger of contact and expense of making them true, yet they are so close that each interposed annular disk of water is held in place, with little chance to do anything but revolve with an average 20 speed about half that of the plates. Each annular disk of water, revolving at such speed, acts like a solid body would, acquiring by its motion such hardness as a stream has when forced from a hose-nozzle under pressure, and 25 the power is absorbed by the plates, rubbing, kneading, dragging, and sucking on these quasi solids.

In the foregoing specification I have incidentally referred to some of the modifications 30 which might be adopted in the practice of my invention; but I have not endeavored to specify all the modifications which might be employed, the object of this specification being to instruct persons skilled in the art to practice my invention in the form at present preferred by me and to enable them to understand its nature, and I desire it to be distinctly understood that mention by me of a few modifications is in no way intended to 35 exclude others not referred to, but which are within the spirit and scope of my invention.

Many of the details and combinations illustrated and above described are not essential to the several inventions broadly considered. 40 All this will be indicated in the concluding claims, where the omission of an element or the omission of reference to the detail features of the elements mentioned is intended to be a formal declaration of the fact that the 45 omitted elements or features are not essen-

tial to the inventions therein severally covered.

What I claim is—

1. In a dynamometer the combination with a series of revolving plates or disks and substantially parallel opposing surfaces not in contact with the plates or pressed against them, of a body of liquid interposed and offering a resistance to the motion and communicating the moment from said plate to said surfaces and means for measuring said moment. 55

2. In a dynamometer the combination with revolving plates or disks and substantially parallel opposing surfaces not in contact with the plates or pressed against them, said surfaces forming independent compartments, of a body or bodies of liquid interposed and offering a resistance to the motion and communicating the moment from said plates to said 60 surfaces and means for measuring said moment. 65

3. In a dynamometer the combination with a revolving plate or disk and substantially parallel opposing surfaces, not in contact with the plate or pressed against it, of a body of freely-circulating liquid interposed and offering a resistance to the motion and communicating the moment from said plate to said 70 surfaces, means for measuring the moment required to drive the revolving part at any certain speed and means for controlling the quantity of liquid contained therein. 75

4. In a dynamometer the combination with a revolving plate or disk and substantially parallel opposing surfaces of a body of freely-circulating liquid interposed and offering a resistance to the motion and communicating the moment from said plate to said surfaces, perforations through one or more of said elements and means for measuring the moment required to drive the revolving part at any certain speed. 85 90

Signed at the city of New York, in the county of New York and State of New York, this 28th 95 day of December, A. D. 1897.

JOHN BURKITT WEBB.
